UNITED STATES PATENT OFFICE.

MAX O. KUHN, OF AKRON, OHIO, ASSIGNOR TO THE FIRESTONE STEEL PRODUCTS COMPANY, OF AKRON, OHIO, A CORPORATION OF OHIO.

RIVETING PRESS.

Application filed April 24, 1925. Serial No. 25,438.

This invention relates to riveting presses and particularly to presses for use in securing lugs or clamps onto demountable rims for vehicle wheels.

The object of the invention in general is to provide an improved press for efficient use in rim manufacture and in particular relatively movable platens, one of which is arranged to support a lug formed with upstanding rivets and the other of which is adapted to first press an apertured rim into proper relation onto said lug with the rivets extending through the apertures and subsequently to rivet over or upset the rivets to secure the lug on the rim.

The foregoing and ancillary objects are obtained by the construction illustrated in the accompanying drawings and described in detail below. It is to be understood that the invention is not limited to the specific construction illustrated and described.

Of the accompanying drawings:

Figure 1 is a front elevation, partly in section, of a press embodying the invention illustrated in use for securing a lug onto a rim;

Figure 2 is a transverse vertical section through said press;

Figure 3 is a section on line 3—3 of Figure 1; and

Figure 4 is a plan of the lower platen.

Referring to the drawings, the press preferably consists of a lower platen 10 and an upper platen 11, the latter being reciprocable toward and from the former in any suitable manner. The platen 10 is formed with a socket 12 for removably receiving lug supporting blocks 13 and 14 which are so formed as to provide between their upper surfaces an inclined tapered slot 15 adapted to snugly receive a lug 16 having the usual bolt hole 17 therein and formed with shoulders 18, 18 for seating against the under surface of a rim indicated at 19 and with an inner face 20 for seating against a rib 21 formed on rim 19. Rivets 16^a, 16^a are formed on lugs 16 and are arranged to pass through apertures 19^a, 19^a in rim 19. Blocks 13 and 14 are held in place by means of a clamping plate 22 secured on platen 10 by screws 23, 23 so as to overhang the front portion of socket 12. So that the socket 12 may be easily and cheaply formed, it is first bored into the platen and then cut into the formation shown, the cylindrical grooves

25, 25 being filled with blocks 24, 24 shaped to fit therein and drawn into place therein by screws 26, 26 to provide a rectangular socket.

The upper platen 11 carries an upsetting or riveting plunger 27 formed with an angularly directed upsetting surface 28. The plunger 27 is received in a socket 28^a in platen 11 and is secured therein by a set screw 29 engaged with a notch 30 in the plunger. In order that the rim 19 will be forced onto rivets 16^a snugly against shoulders 18 and face 20 of the lug prior to the riveting operation by plunger 27, yielding presser elements 31, 31 are carried by platen 11 and are adapted first to engage rim 19 on either side of apertures 19^a or the point where the lug 16 is to be secured. By reference to Figure 1, it will be seen that these elements are directed radially of the rim 19 and are adapted to engage it closely adjacent the lug so as to minimize any flattening action on the rim 19.

Each presser element 31 is arranged to slide in a bore 32 in the platen 11, lubrication of the element being accomplished by a duct 33 in the platen 11 which may have an ordinary grease cup 34 connected thereto. The upper end of each element 31 extends into a chamber 35 in platen 11 and is formed with an enlarged head 36 slideable in said chamber. Fitted in chamber 35 so as to resist sliding of the element 31 upwardly with respect to platen 11 is a resilient pad 37 of rubber formed with a central aperture 38 and with external vertical edges 39, 39 beveled so that the rubber of the pad 37 when compressed may flow laterally in the chamber 35 into the spaces provided by the aperture 38 and beveled edges 39. For retaining the pads in chamber 35 and to facilitate ready replacement thereof, a removable cover plate 40 is arranged over chamber 35 and secured onto platen 11 by means of screws 41, 41. Presser elements 31 are normally held below the lower end of plunger 27 by the pads 37.

In operation, a lug 16 is mounted in the manner shown on plate 10. A rim 19 is then positioned on the lug with the rivets 16^a extending through apertures 19^a. Platen 11 is now moved toward platen 10, elements 31 first engaging rim 19 and forcing it tightly against shoulders 18 and surface 20, the pads 37 permitting the elements to yield during

2
this action so that finally the plunger 27 will engage and rivet over the rivets 16^a as shown in Figure 2. Platen 11 is then elevated, the rim 19 lifted upwardly carrying the lug 16 therewith out of socket 15. Another lug 16 is then placed therein, the rim 19 is manually rotated to the point where another lug 16 is to be secured and the rim again passed on rivets 16^a on the second lug and the operations are repeated as described until the required number of lugs 16 are secured to each rim.

It will appear from the foregoing that by a single stroke of platen 11, the rim and lug 15 are first snugly assembled in the desired relation and subsequently are permanently riveted together. Accordingly, the operations of assembling and securing lugs to rims are easily and rapidly accomplished by 20 a single operation of the press.

Modifications may be resorted to without departing from the spirit thereof or the scope of the appended claims.

What is claimed is:

- 25 1. Apparatus of the class described, comprising a platen, means on the platen for receiving a lug having a rivet thereon so that the latter will project above the platen in such manner that an apertured rim may 30 be mounted on the lug with the rivet extending through the aperture therein, a second platen movable relatively toward and from the first platen, elements on the second platen for engaging the rim and pressing it 35 onto the lug, said elements being directed radially of the rim, yielding pads of resilient material backing said elements and mounted in said second platen so as to flow laterally under compression, and a plunger 40 rigidly carried by the second platen adapted to engage and flatten said rivet, said elements and said plunger being adapted respectively to engage said rim and said rivet at points closely adjacent each other in the 45 order named as the second platen moves toward the first platen.
2. Apparatus of the class described, comprising a platen, means on the platen for receiving a lug having a rivet thereon so 50 that the latter will project above the platen

in such manner that an apertured rim may be mounted on the lug with the rivet extending through the aperture therein, a second platen movable relatively toward and from the first platen, elements on the second platen 55 for engaging the rim and pressing it onto the lug, yielding pads of resilient material backing said elements and mounted in said second platen so as to flow laterally under compression, and a plunger rigidly carried by the second platen adapted to engage and flatten said rivet, said elements and said plunger being adapted respectively to engage said rim and said rivet in the order named as the second platen moves toward 60 the first platen.

3. Apparatus of the class described, comprising a platen, means on the platen for receiving a lug having a rivet thereon so that the latter will project above the platen 70 in such manner that an apertured rim may be mounted on the lug with the rivet extending through the aperture therein, a second platen movable relatively toward and from the first platen, yieldable elements radially 75 mounted on the second platen for engaging the rim and pressing it onto the lug, and a plunger rigidly carried by the second platen adapted to engage and flatten said rivet, said elements and said plunger being adapted re- 80 spectively to engage said rim and said rivet in the order named as the second platen moves toward the first platen.

4. Apparatus of the class described, comprising relatively movable platens, means 85 on one of the platens for supporting a lug having an integral rivet portion with the rivet portion projecting above the platen, yieldable presser elements carried by the other platen for engaging an apertured rim 90 on either side of an aperture therein to force the rim onto the lug with the rivet portion extending through said aperture, and an upsetting plunger on said other platen for engaging and flattening said rivet portion, said presser elements being directed radially of 95 the rim and adapted to engage the rim before the plunger flattens said rivet portion.

MAX O. KUHN.
